UNITED STATES PATENT OFFICE.

CHARLES B. RICHARDS, OF PHILADELPHIA, PENNSYLVANIA.

EXHAUST-VALVE FOR STEAM-ENGINES.

SPECIFICATION forming part of Letters Patent No. 251,948, dated January 3, 1882.

Application filed November 7, 1881. (No model.)

To all whom it may concern:

Be it known that I, CHARLES B. RICHARDS, a citizen of the United States, residing in Philadelphia, Pennsylvania, have invented certain 5 Improvements in Exhaust-Valves for Steam-Engines, of which the following is a specification.

My invention relates to the exhaust-valves of that class of high-pressure or condensing 10 steam-engines in which these valves are arranged one at each end of the cylinder; and the objects of my invention are, first, to force the valve against its seat during that part of its movement in which pressure against the 15 back of the valve is demanded for this purpose, and to relieve the valve or partially relieve it from this pressure during the other part of the movement; and, second, to prevent the waste of steam.

20 In the accompanying drawings, Figure 1, Sheet 1, is a vertical section of part of a steam-cylinder, with the valve-chest and exhaust-valve, the latter being open; Fig. 2, a transverse vertical section on the line 1 2, Fig. 1; 25 Fig. 3, Sheet 2, the same as Fig. 1, with the valve closed; Fig. 4, a perspective view of the valve drawn to a reduced scale; Fig. 5, a perspective view of the pressure-frame and its elastic diaphragm; Fig. 6, a perspective view 30 of the chest cover or bonnet; Fig. 7, a section drawn to a reduced scale, showing the springs which I prefer to use in connection with the valve; and Fig. 8, a sectional view, (reduced,) illustrating a modification of my invention.

35 My invention has no connection with steam-valves, but, as stated in the preamble, is restricted to exhaust-valves and to engines of the class in which there is an exhaust-valve at each end of the cylinder. This should be understood in the outset, for an exhaust slide-valve performs its duty under conditions which differ from those under which a steam-valve operates.

40 A represents in section a portion of the cylinder of a steam-engine, B part of the cylinder-head, and D the exhaust-chest, which communicates through a suitable pipe with the atmosphere if the engine is of the high-pressure type, and with a condenser if the engine is of the condensing class, H being the 45 cover or bonnet of the exhaust-chest.

C is the exhaust-port of the cylinder, d the valve-seat, and E the exhaust-valve, which is of the quadrangular form shown in Fig. 4, and through which extends the opening m. 55

F is a pressure-frame, forming a secondary seat, n, for the valve, this seat corresponding substantially in shape and dimensions with the seat d for the face of the valve, and the opening p in the pressure-frame at its seat corresponding substantially with the port C at the valve-seat d. 60

The above description will apply to valves heretofore used in connection with steam-engines, with this exception, that the opening p 65 in the pressure-frame has been in the form of a recess, and has not extended through the frame, as in my improvement. The pressure-frame, the character of which will be observed by reference to Fig. 5, extends from the back 70 of the valve E into a chamber, f, made preferably in the bonnet H, an elastic diaphragm, P, which may be of sheet-copper, being clamped to the bonnet and to the back of the pressure-frame in such a manner as to be perfectly 75 steam-tight, the diaphragm crossing the space between the frame and the margin of the said chamber f, which is sufficiently larger than the frame to permit the diaphragm to yield to the limited extent desired for permitting 80 the frame to be forced with more or less pressure against the valve E, and to be moved away from the same. This diaphragm P cuts off the communication between the chamber f and the exhaust-chest D when the valve is 85 closed, as shown in Fig. 3.

The dimensions of the back of the pressure-frame are somewhat larger than those of the face of the valve-seat. A block, h, forming in the present instance part of the bonnet H, extends from the latter to within a short distance from the back of the valve E sufficient space being left between the valve and block to permit the free escape of steam in the direction pointed out by the arrows in Fig. 1. The block 95 nearly fills the opening p in the pressure-frame, and it may be stated here that the object of this block is to prevent the waste of steam which would occur in the absence of the block, owing to the presentation of an extended cavity in the frame for the admission of steam at 100 every stroke of the engine. Small projections

on the block, Fig. 6, fit against the walls of the opening of the pressure-frame and serve to steady the latter, while spaces *s s* between the said walls and the block afford free passages for the exhaust-steam to the chamber *f*. Spiral springs *t t*, contained in pockets formed in the bonnet, as shown in Fig. 7, exert a constant pressure against the frame and aid in maintaining its seat in contact with the back 10 of the valve. When the exhaust-valve is closed, as shown in Fig. 3, there is a communication between the interior of the cylinder and the chamber *f*, through the exhaust-port *C*, through the opening in the valve, and through the above- 15 mentioned spaces *s s*, between the block *h* and the walls of the opening in the pressure-frame, so that the pressure of the steam in the cylinder must also be exerted on the back of the pressure-frame and the back of the exposed 20 portion of the diaphragm, and this steam, generally exceeding in pressure that within the exhaust-chest, will exert against the back of the pressure-frame a moderate force, but sufficient to induce the frame to maintain the 25 valve in steam-tight contact with its seat. When the valve is open, as shown in Fig. 1, the chamber *f* will be in communication with the interior of the exhaust-chest, as well as with the interior of the cylinder, and hence the 30 excess of pressure of steam against the back of the pressure-frame will cease, and consequently the valve will move more freely than before and will require less power to operate it.

35 The springs *t* are precautionary devices used for the purpose of keeping the valve against the seat whenever the pressure in the cylinder becomes less than that in the exhaust-chest—a contingency which would be due to the excessive 40 expansion of steam in the cylinder, and would cause the movement of the pressure-frame from the valve and the valve from its

seat. While this movement of the valve and frame would not cause a waste of steam, it could not occur without disagreeable noises and a 45 tendency to bruise the faces of the valve and its seats.

The block *h* may be dispensed with whenever it is practicable to make the pressure-frame shallow, as shown in Fig. 8.

It will be seen that my invention is restricted in its application to exhaust-valves, and could not be adapted to steam-valves contained in a chest wherein the pressure of steam is greater than in the cylinder, the several ports entering into the combination forming the subject of my invention being such that an excess of pressure in the chest would result in the moving of the pressure-frame away from the valve, and this would cause a wasteful leakage of 60 steam.

I claim as my invention—

1. The combination of the exhaust-port *C* and exhaust-chest *D* of the cylinder of a steam-engine with the reciprocating slide-valve *E*, 65 the pressure-frame *F*, interposed between a chamber, *f*, and the interior of the chest, and passages whereby a communication is opened at one time between the said chamber and the interior of the cylinder, and at another time 70 between the cylinder, chamber, and exhaust-chest, in obedience to the movement of the valve, all substantially as set forth.

2. The combination of the valve-chest *D*, valve *E*, and pressure-frame *F* with a block, 75 *h*, extending into the opening of the said frame, substantially as specified.

In testimony whereof I have signed my name to this specification in the presence of two subscribing witnesses.

CHARLES B. RICHARDS.
